(57) **CLAIM**

The ornamental design for a wind tunnel portion, as shown and described.

DESCRIPTION

Fig. 3.1 is a top perspective view of a wind tunnel portion according to our new design;

Fig. 3.2 is a bottom perspective view thereof;

Fig. 3.3 is a front view thereof;

Fig. 3.4 is a back view thereof;

Fig. 3.5 is a top view thereof;

Fig. 3.6 is a bottom view thereof;

Fig. 3.7 is a right side view thereof; and

Fig. 3.8 is a left side view thereof.

The dash-dash broken lines represent unclaimed parts of the wind tunnel portion and form no part of the claimed design. The dot-dash broken represent the boundary between claimed and unclaimed parts of the wind tunnel portion and form no part of the claimed design.
